CLOTHES HANGER

Herschel Lander and William A. Muchlenbeck,
Saginaw, Mich.; Robert H. Brucker administrator of said Herschel Lander, deceased

Application February 1, 1940, Serial No. 316,760

3 Claims. (Cl. 24—123)

Our invention relates to a new and useful improvement in a clothes hanger adapted for use, primarily, indoors although from the description given it will appear that it may be used outdoors as well.

It is an object of the present invention to provide a clothes hanger embodying a supporting line formed from elastic material so that it may be attached at its opposite ends to supporting bodies which may be at different distances apart, the stretchability of the line serving to accommodate it for such attachment.

Another object of the invention is the provision in a clothes hanger of a supporting line having a plurality of supporting hooks slidably mounted thereon and permanently attached thereto so that while they may be slid longitudinally of the line they cannot be removed therefrom.

Another object of the invention is the provision in a clothes hanger of a supporting hook so arranged and constructed as to afford an efficient attachment of the clothes thereon while permitting easy and quick removal of the clothes therefrom.

Another object of the invention is the provision in a clothes hanger of this class of a tubular elastic supporting line having attaching members permanently secured at opposite ends thereof and so arranged and constructed that a firm attachment may be made to the ends of the line and an economical structure provided.

Another object of the invention is the provision of a hook possessed of elasticity and having at its converging end on its inner side, a slightly enlarged space for reception of a portion of the fabric and for facilitating slight expansion of the hook as the fabric is placed in position.

Other objects will appear hereinafter.

It is recognized that various modifications and changes may be made in the detail of structure without departing from the spirit of the invention and it is intended that such variations and changes shall be embraced within the scope of the claims which form a part hereof.

Forming a part of the specification is a drawing, in which:

Fig. 1 is a side elevational view of the invention with parts broken away showing the invention applied between two stationary supports.

Fig. 2 is a slightly enlarged longitudinal vertical fragmentary sectional view of an end portion of the invention.

Fig. 3 is a sectional view taken on line 3—3 of Fig. 1.

Fig. 4 is a sectional view taken on line 4—4 of Fig. 2.

Fig. 5 is a view similar to Fig. 2 of a modified form of the invention.

Fig. 6 is a sectional view taken on line 6—6 of Fig. 5.

Fig. 7 is a sectional view similar to Fig. 6 showing a modified form of the invention.

Fig. 8 is a side elevational view of a modified form of hook used in the invention, and,

Fig. 9 is a side elevational view of a further modified form of hook used in the invention.

As shown in the drawing, the invention embodies a clothes line 15 which is formed tubular and from elastic or stretchable material such as rubber or the like. In the form shown in Fig. 1 and Fig. 2, the ends of the rubber are provided with a fitting. Each of these fittings embodies a neck 16 having a bore 17 formed therethrough

20 communicating at one end with a tapered portion 18 and at the other end with an enlarged recess 19. In assembling the fitting on the end of the line, the end 20 of the line 15 is projected through the bore 17 and a plug 21 is inserted into the end 20, the relation of the outside diameter of the plug 21 and the inside diameter of the bore 17 being such that when the plug 21 is inserted in the end 20, a close fit is provided which serves to clamp the end 20 in the bore 17.

25 This plug 21 is provided with a head 22 which engages in the recess 19. The engagement of the head 22 in the recess 19 is a press fit so that a secure mounting of the fitting on the end of the line is thus afforded. It will be noted that the bore 17 is of slightly smaller diameter than the outside diameter of the line 15 and that when a stretch or strain is exerted on the line 15, it is taken up or resisted to a large extent by the surface of the inclined or tapered portion 18 thus preventing a wearing or tearing of the line 15 at the end of the plug 21.

30 Slidably mounted on the line 15 are supporting hooks each of which comprises an eyelet 23 of slightly larger diameter than the diameter of the

45 line 15 so that these hooks may be easily and quickly moved longitudinally of the line 15. Projecting downwardly from the eyelet is an arm 24 having the upturned hook-forming portion 25. The inner edge of the arm 24 and the hook-forming portion 25 is recessed as at 26 so as to permit a slight springing of the hook-forming portion 25 inwardly and outwardly of the arm 24. This

50 springing characteristic assures a tight gripping of a portion of fabric which is squeezed between the portions 24 and 25.

55

Each of the fittings is provided with an eyelet or loop-forming portion 27 in which engages the eye 28 of a screw hook which is threaded into a stationary support 29. These supports 29 may be of varying widths or distances apart, the stretchability or elasticity of the line 15 permitting the attachment to the stationary supports of various widths while, at the same time, preventing, when the fittings are close together, an undue sagging of the line.

A clothes hanger of this type lends itself admirably for use indoors and provides a simple and inexpensive clothes line which may be easily and quickly mounted in position indoors for supporting small garments such as lingerie, stockings, or the like.

In Fig. 5 we have shown a slightly different form of fitting. In this structure an eyelet 30 is provided with a neck 31 of substantially the same outside diameter as the inside diameter of the line 15 and the end of the line is slipped over the neck 31 and clamped in position by a split metallic band 32 which is clamped around the same.

In Fig. 7 we have shown a structure similar to Fig. 5 excepting that the neck 31' which corresponds to the neck 31 is corrugated to provide depressions and projections 34 over which the end of the line 15 is slipped, a split metallic band 32' being clamped over the structure.

In Fig. 8 we have shown a slightly modified form of hook having an eyelet 23', an arm 24', and a doubled-over hook-forming portion 25' formed integral therewith. This hook is formed from a composition plastic metal material or any other suitable material which will allow a certain spring between the portions 25' and 24'. The space 35, between the opposed edges of the portions 24' and 25', is V-shaped, terminating at its lower end in a restricted passage into which a portion of the garment, such as a stocking or the like, may be squeezed and gripped.

In Fig. 9 we have shown a further modified form of hook providing an eyelet 23'' and an arm 24'' formed integral therewith and stationary relatively thereto. Pivoted to the end of the arm 24'' by a pin 36 is an arm 37 which is adapted to swing behind a swingably mounted keeper 38 after the clothes have been secured in position. The arm 37 may be of the penetrating type such as a pin or it may be used merely to squeeze the fabric against the portion 24''.

In this way we have provided a simple and effective structure for the purposes intended and one which is adapted to accomplish the objects set out.

What we claim as new and desire to secure by Letters Patent is:

1. In a device of the class described: a tubular elastic supporting line; a fitting attachable to the end of said line and comprising an elongated neck having a bore formed therethrough terminating at one end in a tapered portion and at the other end with an axially directed portion terminating

in communication with a recess in said neck, said recess being of larger diameter than said bore, said end of said line being insertible into said bore and projecting through said tapered portion of said bore and into said axially directed portion, said tapered portion of said bore being of larger diameter than the axially directed portion of said bore, said tapered portion of said bore being of smaller diameter than the outside diameter of said line and the outer surface of said line bearing against the inner surface of the tapered portion of said bore; and a cylindrical securing plug inserted into the end of said line and the axially directed portion of said bore for clamping the end of said line therein.

2. In a device of the class described: a tubular elastic supporting line; a fitting attachable to the end of said line and comprising an elongated neck having a bore formed therethrough terminating at one end in a tapered portion and at the other end with an axially directed portion terminating in communication with a recess in said neck, said recess being of larger diameter than said bore, said end of said line being insertible into said bore and projecting through said tapered portion of said bore and into said axially directed portion, said tapered portion of said bore being of larger diameter than the axially directed portion of said bore, said tapered portion of said bore being of smaller diameter than the outside diameter of said line and the outer surface of said line bearing against the inner surface of the tapered portion of said bore; a cylindrical securing plug inserted into the end of said line and the axially directed portion of said bore for clamping the end of said line therein; and a head on said plug engaging as a press fit in said recess.

3. In a device of the class described: a tubular elastic supporting line; a fitting attachable to the end of said line and comprising an elongated neck having a bore formed therethrough terminating at one end in a tapered portion and at the other end with an axially directed portion terminating in communication with a recess in said neck, said recess being of larger diameter than said bore, said end of said line being insertible into said bore and projecting through said tapered portion of said bore and into said axially directed portion, said tapered portion of said bore being of larger diameter than the axially directed portion of said bore, said tapered portion of said bore being of smaller diameter than the outside diameter of said line and the outer surface of said line bearing against the inner surface of the tapered portion of said bore; a cylindrical securing plug inserted into the end of said line and the axially directed portion of said bore for clamping the end of said line therein; and a head on said plug engaging as a press fit in said recess.
